(57) **CLAIM**

We claim the ornamental design for a closure for container, as shown and described.

DESCRIPTION

FIG. 1 is an isometric view of a design of a closure for container according to our invention;

FIG. 2 is a front view of the closure for container shown in FIG. 1, the back view being identical;

FIG. 3 is a left side view of the closure for container shown in FIG. 1, the right side view being identical;

FIG. 4 is a top view of the closure for container shown in FIG. 1; and,

FIG. 5 is a bottom view of the closure for container shown in FIG. 1.

The broken lines shown in FIG. 5 are for illustrative purposes only and form no part of the claimed design.
